T. Crossley.
Woven Fabric.

No. 11,038.

Patented July 6, 1854.

UNITED STATES PATENT OFFICE.

THOMAS CROSSLEY, OF BOSTON, MASSACHUSETTS.

IMPROVEMENT IN WEAVING CUT-PILE FABRICS.

Specification forming part of Letters Patent No. 11,038, dated June 6, 1851.

To all whom it may concern:

Be it known that I, THOMAS CROSSLEY, of Boston, in the county of Suffolk and State of Massachusetts, have invented certain new and useful Improvements in Cut-Pile Carpets and other Similar Fabrics; and I hereby declare the following to be a full, clear, and exact description of the same, reference being had to the accompanying drawings, making part of this specification.

The fabric which mine most nearly resembles is manufactured only in Turkey, and is known as the "Turkey carpet." The process by which it is made is slow and expensive, every individual thread of the tuft or pile being knotted into the body of the carpet by hand, so that it cannot be drawn out, and in consequence this carpet is strong and durable beyond anything which has heretofore been attained in carpets or pile fabrics that are produced by the process of weaving in a loom.

Figure 1 shows two longitudinal sections of the fabric of tapestry carpet, the left-hand portion being upon the line A A and the right-hand portion upon the line B B of Fig. 2. Fig. 2 is a transverse section of the same upon the line C C of Fig. 1. a is the coarse linen warp, which is strained tight in the loom; b, the fine warp; c, the lower shots; d, the upper shots of the filling; f, the tuft or pile. The back of this carpet is composed wholly of linen or cotton, the fine warp being generally made to cross at every two shots of the shuttle. In the above-described specimen it crosses at every third shot. The pile is held down upon the surface of the cotton or linen cloth by a single shot, or, at most, by two shots, as seen at d in Fig. 1. The material which forms the pile is not woven into the body of the cloth, of which it in no case forms a part. Carpets of this description are therefore speedily injured by wear, for the operation of sweeping has to be performed very thoroughly in order to remove the dirt from the tuft or pile, while the latter, being but imperfectly secured to the body of the carpet, is easily disturbed or torn out altogether.

Fig. 3 represents a longitudinal section of an uncut Brussels carpet upon the line D D of Fig. 4. Fig. 4 is a transverse section of the same through the line E E of Fig. 3. g is the

linen warp; h, the upper shot of linen filling; h', the lower shot; k, the pile; m, the "dead" or "stuffing" chain, which will be hereinafter referred to. In carpets of this description, whether cut or uncut in the pile, the different-colored threads not required in the figure upon the face of the goods are made to run longitudinally through the back of the fabric, where they lie, as it were, dormant, and form what is called the "dead" or "stuffing" chain, serving only to give body to the back of the goods. This is rendered necessary in Brussels carpets (the yarns not being dyed in the loom) by the fact that, while but one color is in use upon the surface of the fabric at a time, the others must be at hand to be brought up when required. The yarns which form this stuffing-chain are not woven up and down through the cloth, nor do they form a part of the woven fabric, but lie concealed within it. At no time, therefore, can a greater proportion than one-fifth of the worsted be used upon the face, the remaining four-fifths being thrown into the back, as before stated. Thus it will be seen that a large proportion of the most expensive part of the stock is made to lie dead within the body of the cloth. It will also be seen upon an inspection of Fig. 3 that, except where the colors change, the loops of the pile are held to the surface of the carpet by a single shot of filling. The pile is therefore very liable to be withdrawn or swept out when it is cut, and were the attempt made to fasten it more securely by passing a greater number of shots over it, or by weaving it into the fabric, the loops would be thrown too far apart and the pile would not be sufficiently close.

Both of the above descriptions of carpets require to be woven upon very complicated and expensive looms, the Brussels requiring a Jacquard machine and the tapestry a costly apparatus for printing the yarns in the loom. To avoid these inconveniences and to produce a carpet with a pile that cannot be torn or swept out, and which may at the same time be woven upon a plain loom without Jacquard or dyeing apparatus, is the object of my present invention, which may be described as follows:

Fig. 5 is a cross-section of the carpet upon the line F F of Fig. 6. Fig. 6 is a longitudi-

nal section of the same, the left-hand portion being cut upon the line G G and the right-hand portion upon the line H H of Fig. 5. *n* is a heavy linen or cotton warp, which is kept at all times tightly strained and which forms one side or other of the shed, the other side of which is formed by a woolen warp, which is allowed to remain loose or but slightly strained. These two constitute the only warp of the carpet, and they are constantly upon opposite sides of the shed. *o* is a fine linen, or cotton filling, which is shot below the coarse warp *n*. *p* is a similar filling upon the upper surface of the linen warp. The operation of weaving this carpet is as follows: The shed is opened by depressing the woolen warp and raising the coarse warp. The shot 1 is then thrown in, and in beating up the woolen warp, being comparatively loose, is drawn down to the lower surface of the cloth. The woolen warp is then raised and the linen warp depressed, the shot of filling 2 being thrown in. The beating up draws up the woolen chain around the last shuttle-thread, as before, and the shed is changed again, the woolen passing down and the linen up, and the third shuttle-thread 3 is thrown in. The shed is then changed and the wire is put in to form a loop of the pile. The woolen warp then descends again, and the shuttle-thread 4 is thrown in, and so on, as before. It will be perceived that the pile is thus firmly woven into the body of the carpet and cannot be eradicated therefrom, while by means of the peculiar arrangement which I have adopted of the shuttle-threads above and below the ground-warp the tufts are not separated so far from each other as to make a loose pile, as would be the case were the woolen yarn woven

in the ordinary manner into the surface of a plain fabric; and it is this peculiar construction of the fabric which constitutes the novelty and forms the basis of my invention, and by which I am enabled to produce a fabric with the pile standing close all over its surface at the same time that it is securely interwoven through the body of the carpet. This I believe has never been accomplished before. It is my intention to weave this fabric of uncolored yarns, and after shearing the pile to print the same in the most improved manner. I shall thus produce, at a much reduced cost, a rich velvet carpet having all the beauty of the most expensive tapestry carpets printed in the loom, with the additional advantage that the pile, though dense and close, cannot be swept or torn out from the background, an item of the first importance in a carpet of this description, and one which will render this carpet far more durable than any cut-pile carpet heretofore made, the Turkey carpet alone excepted.

What I claim as my invention, and desire to secure by Letters Patent, is—

The above-described method of weaving a cut-pile fabric—that is to say, interweaving the pile into the body of the cloth—by looping it over a shot of filling on the top of the foundation-warp and under a shot of filling under the foundation-warp, in the manner described, and for the purpose set forth.

In witness whereof I have hereunto set my signature.

THOS. CROSSLEY.

In presence of—

CAUSTEN BROWNE,
H. B. SPINNEY.
